Francis A. Brady, Canandaigua, N.Y.

Filed May 11, 1964, Ser. No. 79,913

Term of patent 14 years

(Cl. D3—10)

FIG. 1

FIG. 2

FIG. 4

FIG. 1 is a top perspective view of a belt showing my new design; portions of the belt have been broken away for convenience of illustration. The portions of the belt not shown are similar in width to the portions shown, are connected so as to form a loop, and are unornamented.

FIG. 2 is a front elevation view thereof;
FIG. 3 is a rear elevation view thereof; and

FIG. 4 is a side elevation view thereof.

I claim:

The ornamental design for a belt, substantially as shown and described.
